OTHER PUBLICATIONS

U.S. Appl. No. 29/353,658, filed Jan. 12, 2010.

(Continued)

Primary Examiner — Ian Simmons*Assistant Examiner* — Rhea Shields(74) *Attorney, Agent, or Firm* — Hayes Soloway P.C.(57) **CLAIM**

The ornamental design for a medical device package, as shown and described.

DESCRIPTION

FIG. 1 is a bottom plan view of medical device package, showing our new design;

FIG. 2 is a top plan view thereof;

FIG. 3 is a left side view thereof from one side, the other side being a mirror image;

FIG. 4 is a front view thereof;

FIG. 5 is a rear view thereof; and,

FIG. 6 is a top perspective view thereof.

In the drawings, the broken lines depict unclaimed subject matter only and form no part of the claimed design.

1 Claim, 6 Drawing Sheets# US D712,244 S
